Primary Examiner — Robert M Spear*Assistant Examiner* — Ryan Harvey*(74) Attorney, Agent, or Firm* — Sand & Sebolt**CLAIM**

The ornamental design for an exercise ball with foot pad, as shown and described.

DESCRIPTION

FIG. 1 is a top plan view of an exercise ball with foot pad. FIG. 2 is a bottom plan view of the exercise device of FIG. 1. FIG. 3 is a rear elevation view of the exercise device of FIG. 1.

FIG. 4 is a front elevation view of the exercise device of FIG. 1.

FIG. 5 is a right side elevation view of the exercise device of FIG. 1; and,

FIG. 6 is a left side elevation view of the exercise device of FIG. 1.

The broken lines illustrate portions of the exercise device which form no part of the claimed design.
